(57) **CLAIM**

The ornamental design for an arboreal pendant as shown and described.

DESCRIPTION

FIG. 1 is a front perspective view of an arboreal pendant; FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of FIG. 1 shown in an alternative position; and,

FIG. 9 is a front perspective view of FIG. 1 shown in an alternative position thereof.

The broken lines shown in the drawings are for the purpose of representing exemplary environmental subject matter and form no part of the claimed design.
